UNITED STATES PATENT OFFICE.

JOHN N. HELTZEL, OF WARREN, OHIO.

CURB AND GUTTER FORM.

Application filed January 31, 1927. Serial No. 164,820.

The present invention relates to concrete forms or molds, and more particularly curb and gutter forms, it being the primary object of the invention to provide a novel and improved curb and gutter form for conveniently producing a curb integral with a gutter or a road slab.

Another object is the provision of a curb and gutter form comprising a novel assembly of the component elements, and having novel features of construction.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

20 The invention is illustrated in the accompanying drawing, wherein—

Figure 1 is a fragmentary perspective view of a curb and gutter form embodying the improvements.

25 Fig. 2 is a cross section adjacent to the template or division plate showing the improved holding device in elevation.

Fig. 3 is a section on the line 3—3 of Fig. 2.

30 Figs. 4 and 5 are cross sections of modified constructions.

Fig. 6 is a cross section of another modification which does not use a front rail.

35 Fig. 7 is a front view of the cam lever and stirrup shown in Fig. 6.

Fig. 8 is a cross section of still another variation for molding a curb integral with a road slab.

40 Fig. 9 is a perspective view of the stake and template bar shown in Fig. 8.

Fig. 10 is a perspective view showing several of the template bars with the face rail removed for finishing the surface of the curb.

45 Fig. 11 is a cross section of the tread portions of the type or back rail shown in Figs. 6 and 8, with a wheel of a carriage, bridge or finishing machine thereon.

50 Fig. 12 is a cross section of superposed back rails.

The form shown in Figs. 1, 2 and 3 comprises the back rail 7, the front rail 8 and face rail 9 of sheet metal. The rails 7 and 8 are of C-shaped cross section. The rail

55 7 comprises the vertical web 10, upper flange

11 having a depending secondary flange or lip 12, and lower or base flange 13 having the upturned secondary flange or lip 14. The front rail 8, which is of less height than the back rail, comprises the vertical web 15, upper flange 16 having the secondary downturned flange or lip 17, and lower or base flange 18 having the secondary upturned flange or lip 19. The face rail 9 has the web 20 and the upper flange 21 provided with the depending secondary flange or lip 22. The lower edge portion of the rail 9 is bent, as at 23, to conform to the contour between the face of the curb and the surface of the gutter.

70 The rails are of suitable length and are laid end to end, as well known in the art, and at suitable intervals longitudinally of the form, templates or division plates 24 are used, only one of such plates being shown.

75 The plate 24 is disposed transversely of the rails in a vertical plane and has the curb portion 25 disposed between the rails 7 and 9, and the gutter portion 26 extending from below the rail 9 to the rail 8. The portion 25 has an edge 27 conforming to the face of the curb, and the upper edge 28 of the portion 26 conforms to the surface of the gutter, and the corner between the edges 27 and 28 is rounded similarly to the lower edge portion 23 of the rail 9, the web 20 of said rail 9 bearing against the edge 27.

80 The plate 24 is formed with a depending arm 29 beyond the portion 25 and a downwardly opening slot 30 between the arm 29 and portion 25, and the plate 24 is provided at its opposite end with a depending arm 31 and a downwardly opening slot 32 between said arm 31 and portion 26. The flanges 11 and 16 have openings 33 for the

85 downward passage of the arms 29 and 31; and the rails 7 and 8 have slots 34 extending downwardly from the openings 33 into the webs 10 and 15, respectively, to receive the portions of the plate 24 uniting the arms 100 29 and 31 with the body of said plate. The arms 29 and 31 thus extend downwardly at those sides of the webs of the rails 7 and

90 8 at the exterior of the form, with the rail webs in the slots 30 and 32, thereby holding the rails 7 and 8 in place. The plate 24 spaces the rails 7 and 8 apart the desired distance, and also maintains said rails in vertical position. The plate 24 has apertures 25 at the upper ends of the arms 29

105

110 7 at the upper ends of the arms 29

and 31 for the engagement of a hook or other implement (not shown) inserted downwardly through the openings 33 for withdrawing the plate after the concrete has set partially.

The form described up to this point is of well known construction, and in combination therewith there is used a device for holding the rails and division plate assembled, as will presently appear.

The holding or connecting device embodies an angle iron 36 or other suitable member disposed transversely above the rails, and hook bolts 37 and 39 engaged through the opposite end portions of said member 36. Nuts 38 and 40 are threaded on the upper terminals of said bolts 37 and 39, respectively, and seat on the member 36, and said bolts have hooks at their lower ends to engage under the flanges or lips 12 and 17 of the rails 7 and 8, respectively. The angle iron or member 36 is provided with means between the ends thereof to engage the rail 9 for holding said rail down in place on the plate 24 and against the edge 27 thereof. For this purpose, a depending arm 41 is secured to the member 36 to bear against the web 20 opposite to the edge 27 of the plate 24, and a depending portion 42 is secured to the member 36 at one side of the arm 41 to bear on the flange 21 of the rail 9. Said flange 21 has an opening 43 for the downward passage of the arm 41.

After the rails and plate 24 are assembled, the arm 41 is readily inserted downwardly through the opening 43, and the hook bolts 37 and 39 then engaged with the flanges or lips 12 and 17. The nuts 38 and 40 being tightened will draw the member 36 downwardly, thereby holding the rails and plate assembled. Thus, the arm 41 holds the web 20 of the rail 9 against the edge 27 of the plate, and the portion 42 bearing on the flange 21 will hold the rail 9 down in place on the plate. At the same time the rails 7 and 8 are drawn upwardly, while the plate 24 receives downward pressure, so as to hold the rails 7 and 8 and plate tightly together. This makes the form thoroughly rigid and substantial. The grout or plastic material is poured in the form as usual and finished between the rails 7 and 9 and between the rails 8 and 9, to finish the upper surfaces of the curb and gutter. It will be noted that the portion 42 spaces the member 36 above the rails 7 and 9 so that the top surface of the curb may be finished under the member 36. The arm 41 may terminate above the lower edge portion 23 of the rail 9, if desired, and when it is formed to abut the portion 23, the portion 42 may be omitted, inasmuch as the lower end of the arm 41 bearing on the portion 23 will hold the rail 9 down in place. It is therefore op-

tional to use the portion 42 bearing on the flange 21 or to use the lower end of the arm 41 bearing on the portion 23.

After the concrete has set sufficiently, the bolts 37 and 39 may be loosened so as to remove the holding or connecting device from the rails, and this permits the face rail 9 to be removed so that the face of the curb may be finished prior to the hardening of the concrete.

The form may be used without the front rail 8, and for this purpose the template or division plate 24 is provided at its forward end above the arm 31 with an upstanding portion 50 having a forwardly and downwardly opening slot 51 forming a hook for the engagement of the lower hook of the rod or bolt 39, with the rail 8 omitted. The bar 36 has several apertures to receive the bolt or rod 39. This arrangement is particularly advantageous when casting a curb integral with a road slab, with the back rail 7 defining the edge or side of the slab and back of the curb and the plates 24 extending inwardly under the face rail 9 into the slab. The hook bolts or rods 39 engaging the portions 50 will be located above the surface of the concrete.

Fig. 4 shows a face rail 9' which in cross section is in the form of a compound curve for producing a curb having a similarly shaped face. The rail 9' has upstanding flanges 21' and 23' at its upper and lower edges, and a depending holding plate 41' secured to the member or bar 36 has notches 42' to engage the flanges of the face rail and thus hold said face rail in place between the front and back rails on the plate 24' which has the edge 27' of the same shape as the face rail. There is also shown a chair 44, bent from a plate of metal, supporting the member 36 from the rail 7, and formed, as at 45, to overlap the web of the rail opposite to the bolt 37 for holding the member 36 in place on the rail. In addition, a stud 46 is shown as secured to the lower flange of the chair 44 to pass downwardly through an aperture 47 in the upper flange of the rail 7 to hold the member 36 in place against movement longitudinally or transversely of the rail 7.

Fig. 5 illustrates a face rail 9'' of the same shape as shown in Fig. 4, excepting that the face rail has the bent back horizontal flange 21'' at its upper edge with a depending lip or secondary flange 22'', in addition to the upstanding flange 23'' at its lower edge.

The depending plate 41'' secured to the member 36 has a notch 42'' to engage the flange 23'' and a depending arm or portion 41' to pass through an opening 43'' in the flange 21'' and bear on the web of the rail 9'', so that the face rail is firmly held in position. Fig. 5 also illustrates a depending

75

80

130

stud or pin 46^{''} secured to the member 36 to pass through an aperture 47^{''} in the upper flange of the rail 7, with a sleeve or enlargement 44^{''} on the stud to form a chair spacing and supporting the member 36 from the rail 7, as well as holding said member 36 in position relatively to said rail.

Fig. 6 illustrates a template or division plate 24^a extending from the back rail 7^a under the face rail 9^a to the edge of a previously completed road slab 52, without using a front rail, such as previously suggested herein. The outer end of the plate 24^a has a depending arm 29^a to engage the rail 7^a, and the plate 24^a has an upstanding portion 50^a at its inner end provided with the hook slot 51^a. The member or bar 36^a located above the plate 24^a and extending across the rails has a depending plate or hanger 41^a between its ends notched to engage over the upstanding flanges 21^a and 23^a of the rail 9^a, and bolts 53 or other means may be employed for securing said rail to said plate or hanger. The hook bolt 37^a extends through the outer end portion of the member 36^a to engage under the upper flange 11^a of the back rail, and a depending spacer member or portion 44^a is secured to the member 36^a to seat on the rail 9^a. A stirrup 54, as shown in Figs. 6 and 7, is adapted to have its loop engaged in the slot 51^a, and a cam 55 is pivoted between and to the terminals of the stirrup to bear on the inner end portion of the member 36^a, in order to draw said member and plate 24^a toward one another at the inner end thereof, for clamping the rails and plate 24^a together. The cam 55 has an arm or handle 56 for convenience in swinging the cam, and said arm bears against the inner end of the member 36^a, as seen in Fig. 6, to lock the parts together. By swinging the arm 56 upwardly to release the cam 55, the stirrup 54 is readily removed from the plate 24^a, and the member 36^a with its plate 41^a and the hook bolt 37^a may be readily removed from the plate 24^a and back rail. It is then possible to finish off the surface of the curb and gutter and the upper edge of the plate 24^a will serve as a template to guide a screed board or member used for finishing the surface of the curb and gutter.

Figs. 8, 9 and 10 illustrate a template or division bar 24^b which, as shown, is in the form of a compound curve, but which may be of any other suitable shape according to the contour of the curb to be formed, and said bar 24^b does not extend to the sub-base as do the plates 24, 24', 24'' and 24^a hereinbefore described, but only extends a slight distance below the surface of the curb. The rail 7^b and its flange 11^b, member 36^b and its plate 41^b, hook bolt 37^b and face rail 9^b are substantially the same as shown in Fig. 6, and the outer end portion of the bar 24^b

has a short depending arm or portion 29^b to engage down through the aperture 33^b in the flange 11^b of the back rail, with an aperture 35^b to facilitate lifting the outer end of the bar from the back rail. The inner end of the bar 24^b is welded or otherwise secured to a stake 31^b which is driven into the sub-base to support the inner end of said bar. Said stake projects above the inner end of the bar and has an aperture 51^b for the engagement of the hook at the lower end of a bolt or rod 39^b that engages through the inner end portion of the member 36^b.

With the form construction shown in Figs. 8, 9 and 10, the road slab 52^b may be completed up to the back rail 7^b, and the stakes 31^b are then driven down through the slab while the same is still plastic, the outer ends of the bars 24^b being engaged in the openings or apertures 33^b of the back rail 7^b. The face rail 9^b is then applied, being of a shape to fit and seat on the bars 24^b, as seen in Fig. 8, and the member 36^b is then attached to the back rail and stakes, to clamp the parts together. Additional material may then be poured between the back and face rails so as to form the curb, which amalgamates with the slab, to form an integral curb and road slab. After the material has set sufficiently, the face rail 9^b may be removed by detaching the hook bolts 37^b and 39^b from the back rail and stakes, respectively. The surface of the curb may then be finished off conveniently by sliding a longitudinal screed board or member 58 on the bars 24^b, as seen in Fig. 10, said bars serving as templates. Then, by lifting the outer ends of the bars 24^b from the back rail and pulling the stakes 31^b, the bars and stakes are removed, after which the slots left in the concrete may be finished off or filled in.

The upper flange 11^a of the back rail as seen in Fig. 6 and the upper flange 11^b of the back rail as shown in Figs. 8, 9, 10 and 11, are arranged on a bevel or slope away from the web of the rail, so as to provide a single line of contact for a wheel 59 travelling on the rail. This provides a clean contact between the back rails at opposite sides of a road under construction and the wheels of carriages travelling on said rails, it being the practice to run bridges, finishing machines, and the like, on the rails during the building and completion of the road. It will be noted that sand, gravel and other materials which may fall on the upper flange of the back rail will be shed outwardly off the rail, so as not to accumulate thereon, and the wheels of the carriages will thus have a perfect contact with the rails along lines directly above the webs of the rails, as seen in Fig. 11. The carriage will therefore be guided along a true line, which is especially

desirable when using a finishing machine, in order that the surface of the road will be formed accurately and smoothly. With tread flanges as shown in Figs. 1 to 5, inclusive, it is possible for sand, gravel and other particles to accumulate or lay on the tread flanges, so that wheels of finishing machines or other carriages travelling on the rails, in passing over the particles thereon, will vibrate the machine. However, with the sloping tread flanges as seen in Figs. 6 to 11, inclusive, the particles will roll or slide off the tread flanges. It will be noted that the wheels contacting with the rails along lines immediately above the webs of the rails will transmit the weight and pressure directly downward in the planes of the rail webs, in order to prevent any tendency for the weight and pressure of the machine or carriage to bend the tread flanges of the rails downwardly, and said tread flanges receive no appreciable downward bending strains, although they stiffen and reinforce the rails.

When using the forms shown in Figs. 6, 8, 9 and 10, the back rail 7^c, as seen in Fig. 12, may be of the height of the curb, and may be seated on and secured to a rail 7^a that is employed for the construction of the road slab. Thus, the rail 7^a is of the height or thickness of the road slab, and after the road slab is completed the back rail 7^c may be seated and secured on the rail 7^a for completing the curb. If this construction is used in the form shown in Fig. 6, the rail 7^a is first used to define the edge of the slab 52 and is then set outwardly to required distance away from the slab into the line of the rail 7^a as seen in Fig. 6, but the rails 7^c and 7^a are especially intended for the form shown in Figs. 8, 9 and 10.

As shown in Fig. 6, the stirrup or member 54 is connected directly with the portion 50^a of the plate 24^a, and said stirrup may also be used with the construction shown in Figs. 1 to 5, inclusive, and in Figs. 1-5 the hook bolt or member 39 is connected with the template or division plate through the medium of the front rail, although said hook bolts may be connected directly with the portions 50 of the templates or division plates. As seen in Fig. 8 the hook bolt or member 39^b is connected with the template or bar 24^b through the medium of the upper portion of the stake, and each form the inner end portion of the template has an upstanding portion with an aperture or slot for the engagement of the hook bolt or other member of the device which clamps the back and face rails and template together.

Having thus described the invention, what is claimed as new is:—

1. A holding device for a curb and gutter form having members adapted for connection with a back rail and a template of the

form, a member intermediate said members to engage a face rail bearing on the template, and means for applying pressure tending to raise the first named members and depress the third named member. 70

2. A holding device for a curb and gutter form having adjustable members to connect with a back rail and a template of the form, and a member intermediate said members to engage a face rail bearing on the template. 75

3. A holding device for a curb and gutter form comprising depending adjustable members to connect with a back rail and a template of the form, and a depending member between said members to engage a face rail bearing on said template. 80

4. A holding device for a curb and gutter form comprising a member to extend across the back and face rails and above a template of the form, and depending members connected to said member to connect with the back and face rails and the template and arranged for applying upward pressure to the template and back rail and 90 downward pressure on the face rail.

5. A holding device for a curb and gutter form comprising a member to extend across the back and face rails and above the template of the form, depending adjustable members connected with said member and adapted to connect with the template and back rail for moving the first-named member toward said template and back rail, and a depending member connected to the first-named member to engage and bear downwardly on the face rail. 100

6. A holding device for a curb and gutter form comprising a member to extend across the back and face rails and above the template of the form, members adjustably connected with the first-named member to connect with the template and back rails, and a depending member connected to the first-named member between the second-named members to engage and bear on the face rail. 110

7. An adjustable holding device for the template and back and face rails of a curb and gutter form having portions to connect with the template and back rail to exert an upward pressure thereagainst, and a portion intermediate said portions to bear downwardly against the face rail. 115

8. The combination with a curb and gutter form including a back rail and a template having portions fitted together by the downward movement of the template relatively to said rail, and a face rail seated against the template, of an adjustable holding device having portions to connect with the back and face rails and template to exert downward pressure on the face rail and upward pressure on the template and back rail. 120

9. The combination with a curb and gut- 125

- ter form including a back rail and a template having portions fitted together by the downward movement of the template relatively to said rail, and a face rail seated against the template, of an adjustable holding device having portions to connect with the template and back rail for drawing them upwardly, and having a depending portion between the aforesaid portions thereof to engage the face rail to exert downward pressure thereon.
10. The combination with a curb and gutter form including a back rail and a template having portions fitted together by the downward movement of the template relatively to said rail, and a face rail seated against the template, of an adjustable holding device comprising a member extending over said rails and members depending from said member to connect with the back and face rails and template for exerting downward pressure on the face rail and upward pressure on the template and back rail.
11. The combination with a curb and gutter form including a back rail and a template having portions fitted together by the downward movement of the template relatively to said rail, and a face rail seated against the template, of an adjustable holding device comprising a member extending above said rails, members connected with the template and back rail and adjustably connected with the firstnamed member for drawing said firstnamed member and the template and back rail toward one another, and a depending portion carried by the firstnamed member to engage and bear downwardly against the face rail.
12. The combination with a curb and gutter form including a back rail and a template having portions fitted together by the downward movement of the template relatively to said rail, and a face rail seated against the template, of a holding device comprising a member extending above said rails, means for connecting said member and the template and back rail to draw said template and back rail and said member toward one another, and means carried by said member to engage and bear downwardly against the face rail.
13. The combination with a curb and gutter form including a back rail and a template having portions fitted together by the downward movement of the template relatively to said rail, and a face rail seated against the template, of an adjustable holding device comprising a member extending over said rails, means for connecting said member with the template and the back and face rails for exerting downward pressure on the face rail and upward pressure on the template and back rail, and a supporting member between the firstnamed member and back rail.
14. The combination with a curb and gutter form including a back rail and a template having portions fitted together by the downward movement of the template relatively to said rail, and a face rail seated against the template, of an adjustable holding device comprising a member extending over said rails, means for connecting said member with the template and the back and face rails for exerting downward pressure on the face rail and upward pressure on the template and back rail, and a supporting member carried by the firstnamed member to seat on the back rail, said supporting member and back rail being adapted to engage one another to prevent displacement of the firstnamed member on said back rail.
15. The combination with a curb and gutter form including a back rail and a template having portions fitted together by the downward movement of the template relatively to said rail, said template having an upstanding portion, and a face rail seated on the template between said back rail and upstanding portion, of an adjustable holding device having portions to connect with the back and face rails and said upstanding portion for clamping the rails and template together.
16. The combination with a curb and gutter form including a back rail, a template, the outer end of the template and back rail having portions fitted together by the downward movement of the template relatively to said rail, said template having an upstanding portion at its inner end, and a face rail seated on the template between said portion and back rail, of an adjustable holding device having a portion to connect with the face rail and other portions to detachably engage said upstanding portion and back rail for clamping said rails and template together.
17. A template having a portion to engage a rail, and a stake connected to said template.
18. A template having a portion at one end to connect with a rail, and a stake connected to the other end of the template.
19. A template having a portion to engage a rail, and a stake connected to said template and having a portion extending above the template.
20. A template having a portion at one end to engage a rail, and a stake connected to the other end of the template and having a portion extending above the template and formed with an aperture.
21. A form of the character described comprising a rail, a stake, and a template connecting said rail and stake.
22. A form of the character described comprising a rail, a stake, and a template secured to the stake, said template and rail having portions to fit together by the down-

ward movement of the template relatively to the rail.

23. A form of the character described comprising a rail, a stake, and a template secured to the stake, said template and rail having portions to fit together by the downward movement of the template relatively to the rail, the stake having a portion extending above the template.

10 24. A form of the character described comprising a rail, a stake, a template connecting said rail and stake, a face rail seating on the template, and a holding device connected with said rails and stake for clamping the rails and template together.

15 25. A form of the character described comprising a rail, a stake, a template secured to the stake, said template and rail having portions fitted together by the downward

movement of the template relatively to said rail, a face rail seated on the template, the stake having a portion extending above the template, and a holding device connected with said rails and said upstanding portion of the stake for clamping said rails and template together.

20 26. A form rail having an upper beveled flange.

27. A form rail having a tread flange sloping from the rail web.

30 28. A form rail having a web and an upper flange, with said flange so formed as to provide a single line of wheel contact directly above the web.

35 In testimony whereof I hereunto affix my signature.

JOHN N. HELTZEL.
